UNITED STATES PATENT OFFICE.

EUGENE HAYWARD, OF CLAYTON, MICHIGAN, ASSIGNOR OF ONE-THIRD TO JOHN T. LUEDER AND ONE-THIRD TO JOHN B. MORRIS, BOTH OF CHICAGO, ILLINOIS.

ELECTRICAL CONNECTION FOR RAILWAY-RAILS.

No. 842,545.

Specification of Letters Patent.

Patented Jan. 29, 1907.

Application filed August 21, 1905. Serial No. 275,117.

To all whom it may concern:

Be it known that I, EUGENE HAYWARD, a citizen of the United States, and a resident of the city of Clayton, in the county of Lenawee 5 and State of Michigan, have invented certain new and useful Improvements in Electrical Connections for Railway - Rails; and I do hereby declare that the following is a full, clear, and exact description of the same, reference being had to the accompanying drawings, and to the letters of reference marked thereon, which form a part of this specification.

This invention relates to improvements in 15 electrical connections for railway-rails.

Heretofore in forming electrical connections of this class it has been customary to unite the abutting ends of the rails by means of wires, which have been secured at their 20 ends to the ends of the rails and between their points of connection have extended along the side of the rails, generally on the outer side of the fish-plates and entirely exposed. This method has been more or less 25 objectionable by reason of the fact that the wires often become disconnected either through accident or by being tampered with by unauthorized parties.

The object of this invention is to provide a 30 means for forming an electrical connection at rail-joints which will be entirely inclosed and concealed between the fish-plates, thereby preventing its being tampered with or injured and in which the bonding-wire forms a 35 very firm and secure contact.

The invention consists in the matters hereinafter described, and more fully pointed out and defined in the appended claims.

In the drawings, Figure 1 is a fragmentary 40 side elevation of a rail-joint with the fish-plates removed and provided with means embodying my invention. Fig. 2 is a section taken on line 2 2 of Fig. 1. Fig. 3 is a perspective view of the bonding-wire.

45 As shown in said drawings, A and A' represent abutting rails, which may be of any preferred construction, but which are shown as ordinary T-rails and the webs *a* of which are provided in their ends near the base of the 50 rails with complementary recesses or notches, which when the rails are in place, as shown in Fig. 1, form an approximately semicylindric

aperture A² through the joint. The inner ends of said notches or recesses are directed downwardly and form cylindric seats *a'*, extending transversely of the rail. Seated within said aperture A² is the bonding-wire, (indicated as a whole by B,) and which, as shown more clearly in Fig. 3, comprises a wire or rod *b* of any preferred material and provided with downwardly - bent ends on each of which is secured a contact-plug *b'*. Said plugs, as shown, are tubular, though obviously they may be solid, and are apertured in their sides to receive the ends of said wire 65 and are provided on their ends with outwardly-directed peripheral flanges *b*², adapted to retain the wire in position when seated in said aperture. Said plugs engage in the cylindric seats at the ends of said recesses and the 70 wire *b* extends longitudinally of the rails in the aperture A², and, as shown, is curved downwardly centrally thereof to provide sufficient length to prevent breaking the connection by contraction of the rails due to 75 changes of temperature, though obviously the wire may assume any other preferred form.

Fish-plates C C of any preferred construction are engaged upon the rails in the usual 80 manner and engage with their lower edges against the flanges *b*², thereby rigidly holding said bonding-wires in place.

The operation of my device is as follows: When the rails are placed end to end in the 85 track, the notches or recesses in the ends thereof form an aperture through the rails at the joint, the inner ends of which are directed downwardly and adapted to receive the plugs *b'*, which are held in place by their 90 flanges *b*². The connecting-wire *b*, being rigidly engaged to said plugs, forms the electrical connection between the rails, and owing to the central bend therein permits the contraction of the rails without rupturing the connection. 95

While I have shown the rails as ordinary T-rails, it is obvious that any other preferred form of rail may be employed, and the aperture therethrough may assume various forms and the bonding-wire connecting the rails may 100 be of any preferred shape, and I therefore do not purpose limiting this application for patent otherwise than as disclosed in the prior art and as stated in the claims, as obviously many

details of construction may be varied without departing from the principles of my invention.

I claim as my invention—

5. 1. In a device of the class described the combination with abutting rail ends having an aperture therethrough, a contact-plug extending through the rail-webs at each end of said aperture and a conductor connecting 10 said plugs and concealed in said aperture.
2. In a device of the class described the combination with abutting rails having a recess therein of a bonding-wire concealed in said recess and a contact-plug connected at 15 each end thereof and seated in recesses at the ends of said aperture.
3. In a device of the class described the combination with abutting rails provided at the joint with an aperture therethrough having cylindric seats at the end thereof of transverse plugs engaged in said seats peripheral flanges thereon for limiting the inward movement of said plugs and means contained in 20 said aperture for connecting said plugs.
25. 4. The combination with abutting rails, each provided with a cylindric seat and a recess opening therefrom to the end of the rail of a plug in each seat, a bonding-wire engaged with each plug and lying in said recesses, a 30 peripheral flange on one end of each plug and means for holding said plugs in place.
35. 5. In a device of the class described the

combination with two abutting rail ends having an aperture in each and provided with a seat at the base of each aperture, a tubular contact-plug seated in each seat, a conductor connected to said plugs and flanges on each of said plugs adapted to limit the transverse movement of the same: 35

6. A bonding-wire of the class described 40 comprising a plurality of transverse tubular plugs having an aperture opening into the same at an angle thereto, a wire having its ends projecting through said aperture and into said tubular plugs and a flange on one 45 end of said plugs.

7. In a device of the class described the combination with abutting rail ends having an aperture through the rail-web, a seat in each rail-web adjacent the end of said aperture, contact-plugs engaged in said seats transversely of the web, a wire in said aperture rigidly engaged to said contact-plugs and means on the ends of said contact-plugs 50 adapted to bear against the webs of the rail 55 and acting to hold said wire from lateral movement.

In testimony whereof I have hereunto subscribed my name in the presence of two subscribing witnesses.

EUGENE HAYWARD.
